HEATING APPARATUS

John Robert Farbridge, Colombo, Ceylon

Application November 5, 1931, Serial No. 573,288
In Great Britain November 7, 1930

5 Claims. (Cl. 126—109)

This invention relates to heating apparatus of the kind comprising a plurality of separated flues or passages through or on each side of which the heating medium passes, and on each side or 5 through which the medium to be heated passes.

The invention relates particularly to apparatus of this kind adapted to yield a supply of hot air for drying and other purposes and has more particular reference to the apparatus covered by 10 the present applicant's co-pending application Serial No. 462,324 of which the present application is a continuation in part.

An object of the invention is to provide improvements in apparatus of the above kind 15 whereby it is possible to obtain a higher ratio of economy in regard to the quantity of fuel consumed by the apparatus relatively to the amount of heat imparted to the air or other medium passing through the apparatus and to control 20 and conserve the temperature and heat of such apparatus.

With this and other objects in view the invention consists in the features to be hereinafter described, illustrated in the drawings and defined 25 in the appended claims.

In the accompanying drawings

Figure 1 is a front elevation of a form of apparatus according to the invention which is adapted to burn liquid fuel;

30 Figure 2 is a part sectional plan taken on the line H—H of Figure 1;

Figure 3 is a part sectional front elevation taken on the line J—J of Figure 2, and

35 Figure 4 is a sectional side elevation taken on the line K—K of Figure 2.

The general construction and arrangement of apparatus according to the particular embodiment herein described is similar to that disclosed in the said copending application Serial No. 462,324 and need not be fully described herein, it being sufficient for an understanding of the present invention to mention that it comprises air heating chambers forming a plurality of isolated flue passages formed from groups of tubular elements, hot furnace gases being caused to traverse such flue passages so that heat is imparted to air or other medium which passes through the tubular flue-forming elements, the hot air or other heated medium being received

50 in a suitable chamber while the furnace gases after traversing the flue passages are led away through a main smoke flue to a chimney or the like which may be located at the back of the apparatus or at the front as desired.

55 In carrying the invention into effect in one

convenient manner and as applied to apparatus of the kind described in the said co-pending application Serial No. 462,324 which comprises a central fireplace or combustion chamber 1, flues 2 and multitubular air-heating or flue-forming 60 elements 3 carried by top and bottom tube plates 4, 5, the flue-forming members 3 are inclined towards each other in an upward direction so that they enclose a combustion chamber of substantially triangular cross section. 65

The arrangement of the tube plates 4, 5 for the flue-forming elements is substantially the same as that disclosed in the earlier specification but the tube plates are modified somewhat in order to suit the inclined arrangement of tubes or flue-forming elements, the upper tube plate 4 being of angular form and built up of a plurality of angular members which are supported at their ends upon a framework 6. 70

The combustion chamber 1 enclosed by the 75 tubes on either side is thus of substantially triangular form in cross section and the arrangement of the inclined tubes has the advantage that no brickwork or other furnace crown is required while it has the further advantage that the apparatus may be made perfectly smoke tight and a comparative saving in the cost of manufacture and construction thereof is made possible. 80

The said air-heating elements 3 are so spaced that the flues or chambers enclosed between them 85 decrease progressively in width from the front of the apparatus towards the back as is clearly shown in Figure 4. This arrangement is adopted because in apparatus of the above kind the velocity of the gases in each flue passage diminishes gradually in a direction away from the smoke outlet 7 so that the velocity of the gases through the flue passages at the back of the apparatus will be at a maximum and the velocity of the gases through the flue passages at the front will be a 90 minimum. This difference in the velocity of the furnace gases is thus compensated in the present invention so as to obtain a uniform heating of the flue-forming elements by successively increasing the spacing of the flues in a direction 100 away from the chimney. Alternatively, the spacing of the flues may be otherwise varied, so that this effect of uniform heating is obtained. 95

The tubes 3 are reduced somewhat in diameter for a short distance at their upper ends, as indicated at 34^a, from the part where they leave the neck 3^b of the top tube plate 36^c and enter stuffing boxes 3^a formed in the latter the tubes touching one another in the neck of the tube plate but being separated from each other, in the 110

neighbourhood of their reduced portions, by annular spaces which permit of packing being applied all around these portions of the tubes.

Retarders or baffles 3^a are inserted in the tubes 5 to prevent too rapid passage of the air to be heated, these retarders or baffles causing the air to circulate in contact with the internal surfaces of the heated tubes and thus increasing the rate at which the air absorbs heat from the tubes and 10 adding to the efficiency of the apparatus.

The smoke flue passage 9 provided at the bottom of the apparatus is formed as a separate unit, this having the advantage that the efficiency of the apparatus as regards the elimination of any 15 smoke or other impurities from the furnace entering the heated air will not be impaired in any way due to there being any unevenness in the flooring construction where it is desired to install the apparatus.

20 This smoke flue unit comprises a plate 10 having sides 11 welded or otherwise secured thereto and channel irons 12 or other suitable supports riveted or otherwise secured to such sides and adapted to support in part the lower tube plates 25 5 for the flue-forming elements 3, the supports for the latter at the bottom being also constituted by angle irons 13 or other suitable means secured within the opposite side walls of the heating apparatus.

30 The sides of the smoke flue unit are provided with valves 14 for controlling the flow of the furnace gases to the smoke outlet 7 while the top plate of the said unit is adapted to support fire-bricks 15 or any other suitable structure enclosing and forming the lower part of the combustion chamber. The said valves 14 for controlling the flow of the furnace gases from the flue passages 2 to the smoke outlet 7 via the main smoke flue 9 may take the form of flap valves common 40 to all the outlets from each battery of flues or a separate flap valve may be provided for each flue passage outlet, the said valve or valves being suitably supported in position and adapted to be operated from the outside by hand wheels 16 so as to regulate the volume of gases allowed to pass through the multitubular smoke flues 2.

By so regulating the volume of gases passing through the flue passages the temperature of the hot air passing through the interior of the flue-forming elements can be regulated as desired.

50 The apparatus is fitted with a liquid fuel burner 17 which is adapted to give a vertical flame and is disposed in the lower half of the combustion chamber and supplied with air and fuel through pipes 18, 19 respectively. A fan 20 is provided at the smoke outlet 7 whereby it is possible to have a complete mechanical control of the combustion in the furnace, the said fan operating to draw and/or force the required amount of air into the furnace to complete combustion while it may also be arranged to operate so as to withdraw the gases from the furnace.

60 By the use of a fan or like device the heater is under complete control and is not affected by atmospheric changes which interfere with the draught of an ordinary smoke chimney.

A preheating chamber 24^a is provided at the front of each air-heating chamber and the air supply to the burner 17 is conveyed by a pipe 24^b 70 through one chamber and the oil supply is like-

wise conveyed to the burner through the other chamber by a pipe 24^c.

The air is caused to flow downwardly through the tubes 3 by providing a cold air chamber 38 having an inlet 39 under the control of a regulating valve 40 and a fan 41 adapted to draw the air downwardly through the tubes and through a hot air chamber 42. The openings 5^a in the bottom tube plate are graduated in size, being larger the nearer they are to the furnace.

I claim:

1. Heating apparatus comprising in combination, walls defining a combustion chamber, walls defining a heat exchange chamber having communication with the combustion chamber so that the combustion gases may flow from the combustion chamber through the heat exchange chamber, means for withdrawing the combustion gases from the apparatus after said gases have traversed the heat exchange chamber, and banks of tubes disposed within the heat exchange chamber so as to form flues, for the passage of the combustion gases, of successively increased areas in a direction away from the end of the combustion chamber where the combustion gases are discharged from the apparatus, the said tubes, which serve for the passage of the medium to be heated, having inlet openings which, in each bank of tubes, are successively decreased in size in a direction away from the combustion chamber. 105

2. Heating apparatus comprising in combination, walls defining a combustion chamber, walls defining a heat exchange chamber which receives the combustion gases from the combustion chamber, a fan disposed adjacent to one end of the combustion chamber and adapted to control the flow of the combustion gases and to exhaust same and a plurality of banks of tubes disposed within the heat exchange chamber with the end tubes of each row in close proximity to the adjacent walls of the said heat exchange chamber and with the tubes in each bank in close contact with each other, the said banks of tubes being also disposed within the heat exchange chamber so as to form flues, for the passage of the combustion gases, of successively increased areas in a direction away from the end of the combustion chamber where the said fan is located, and the said tubes, which serve for the passage of the medium to be heated, having inlet openings which, in each bank of tubes, are of successively increased areas in a direction away from the combustion chamber. 115

3. Heating apparatus according to claim 2 comprising a fan adapted to control the passage through the tubes of the medium to be heated. 120

4. Heating apparatus according to claim 2 comprising a stuffing box for the ends of said tubes, which latter have their end portions of reduced diameter adapted to permit of the entire circumferential surfaces of the tubes being packed, the 125 portions of the tubes of greater diameter being adapted for close contact with one another.

5. Heating apparatus according to claim 2 having a heat exchange chamber on each side of the combustion chamber and having the banks of 130 tubes in the one heat exchange chamber inclined, at the top, towards the bank of tubes in the other heat exchange chamber.

JOHN ROBERT FARBRIDGE. 145
